JASPER BLACKBURN,
by Higdon & Tongue, 1913.

UNITED STATES PATENT OFFICE.

JASPER BLACKBURN, OF KIRKWOOD, MISSOURI.

EARTH-ANCHOR.

1,080,041.

Specification of Letters Patent.

Patented Dec. 2, 1913.

Application filed March 11, 1913. Serial No. 753,609.

To all whom it may concern:

Be it known that I, JASPER BLACKBURN, a citizen of the United States, and resident of Kirkwood, St. Louis county, Missouri, have 5 invented certain new and useful Improvements in Earth-Anchors, of which the following is a specification containing a full, clear, and exact description, reference being had to the accompanying drawings, forming 10 a part hereof.

My invention relates to improvements in earth anchors, and the object of my invention is to provide an improved construction of the type of anchor known as the inverted 15 cone anchor, which is provided with a flat base or body portion having a sleeve projecting upwardly from the base to provide means for attaching the anchor to an anchor rod, and also provided with a plurality of 20 radially arranged, spaced apart pins which vary in height and which form a surface having a maximum of holding efficiency in broken rock, or the like which is tamped upon the anchor.

With the above purposes in view my invention consists in certain novel features of construction and arrangement of parts as will be hereinafter described, pointed out in the claims and illustrated by the accompanying 25 drawings, in which—

Figure 1 is a plan of one of my improved anchors; Fig. 2 is a transverse sectional elevation taken on the line 2—2 of Fig. 1; and Fig. 3 is a view on a reduced scale, showing 30 my improved anchor as in use.

Referring by numerals to the accompanying drawings: 5 designates the base or body portion of the anchor which is substantially disk-shape and has at its periphery a rib 6 40 which projects above the upper face of the base. At the approximate center of the base there is a sleeve 7, the lower end of which is formed of a size to provide a seat 8.

An ordinary anchor rod 9 is extended 45 through the sleeve 7 and a nut 10 is secured to the end of the rod and occupies the seat 8 formed in the bottom of the base. Formed on the upper surface of the base and integral therewith are the radially arranged 50 rows of pins or projections 11 which are of

graduate sizes, the innermost pins of each row being the longest.

12 designates pins which are formed like and arranged between each row of the pins 11. The two pins 12 are slightly higher 55 than the pins 11 next adjacent them. As shown in Fig. 2, the tops of the pins 11 and 12 form a surface something after the appearance of a terraced pyramid.

It is obvious that when broken stone or the like is placed upon the pins and tamped the stone will be forced over the downwardly and outwardly inclined surface formed by the tops of the pins to embed in the earth surrounding the bore or opening in which 65 the anchor is placed, as shown in Fig. 3, and that the uneven surface presented by the pins of varying heights is a surface affording a maximum of holding efficiency in the tamped broken stone. 70

I claim:

1. As a new article of manufacture, an earth anchor, comprising a flat base arranged to be secured to an anchor rod, and a plurality of pins of graduate sizes formed on 75 the upper face of the base.

2. As a new article of manufacture, an earth anchor, comprising a flat disk-shape base, a sleeve formed integral with the base arranged to receive an anchor rod and enlarged at its bottom to receive a nut on the end of the anchor rod, and a plurality of pins on the upper surface of the base arranged in radial rows, and the pins of each row being of graduate sizes. 80

3. As a new article of manufacture, an earth anchor, comprising a flat base and a plurality of pins formed integral with the base, said pins being arranged in radial rows and of graduate sizes, and pins arranged between the rows of heights greater than the pins in the rows next adjacent them. 85

In testimony whereof, I have signed my name to this specification, in presence of two subscribing witnesses.

JASPER BLACKBURN.

Witnesses:

E. L. WALLACE,
JOHN C. HIGDON.
